UNITED STATES PATENT OFFICE.

LOUIS TOUPIN, OF WEST WARWICK, RHODE ISLAND, ASSIGNOR TO CROMPTON COMPANY, OF CROMPTON, RHODE ISLAND, A CORPORATION OF RHODE ISLAND.

GUIDE-HOLDER FOR PILE-CUTTING MACHINES.

1,248,205.

Specification of Letters Patent. Patented Nov. 27, 1917.

Application filed June 7, 1915. Serial No. 32,572.

To all whom it may concern:

Be it known that I, LOUIS TOUPIN, of West Warwick, in the county of Kent and State of Rhode Island, have invented certain new and useful Improvements in Guide-Holders for Pile-Cutting Machines; and I do hereby declare the following specification, taken in connection with the accompanying drawings, forming a part of 10 the same, to be a full, clear, and exact description thereof.

The invention relates to a guide-holder for holding the knife-guide in a machine for cutting pile fabrics. Heretofore it has 15 been customary to solder the knife-guide to the guide-holder, thereby making the two stationary with relation to each other. With such a construction and arrangement great skill and care must be exercised in soldering the knife-guide to the guide-holder 20 as the slightest turning of the knife-guide from its proper position will result in crimp cutting of the pile and produce an imperfect fabric. Furthermore when the 25 guide-holder is soldered to the knife-guide it interferes with the free manipulation of the knife-guide while grinding or sharpening the same.

It is the object of the present invention to 30 obviate these objectionable features and to produce a guide-holder in which the knife-guide is removably mounted, so that when a knife-guide is broken, a new one can be easily and quickly mounted in the guide- 35 holder in proper position and without the exercise of any skill.

To this end the invention consists in the 40 novel form of guide-holder hereinafter described and more particularly set forth in the claims. In describing the invention in detail reference will be made to the accompanying drawings, in which—

Figure 1 is an end view of my novel 45 guide-holder.

Fig. 2 is a side view of the same.

Fig. 3 is a top plan view of the guide- 50 holder with a knife-guide mounted therein.

Fig. 4 is a side view of the same.

Fig. 5 is a side view of the knife-guide.

Fig. 6 is a top plan view of the same.

Fig. 7 is an end view of the same.

Referring to the drawings, the guide- 55 holder comprises a wedge-shaped body portion 1 having a flat circular end portion 2.

Secured to the end portion 2 is a lateral

stud 3 provided with a cam-projection 4 of the usual construction. The body portion 1 is provided upon the side opposite to the stud 3 with a downwardly extending lip 5 arranged substantially parallel with said 60 body portion to form a slot or groove 5' and upon the same side with an upwardly extending lip 6 arranged substantially parallel with said body portion to form a slot or groove 6', as shown in Fig. 1. 65

The knife-guide 7 is wedge-shaped and is provided with a longitudinal slot or channel 8 to receive the knife. Said longitudinal slot 8 makes the large end of the knife-guide 7 U-shaped in cross-section, as 70 shown in Fig. 7. The knife-guide 7 is mounted in the guide-holder by inserting the pointed end in the slot 6' and forcing said knife-guide forward until it is wedged in position. As the knife-guide is forced 75 forward the downwardly extending lip 5 enters the slot 5' and as said slot 5' is narrower than the leg of the U-shaped end portion which engages the same, and as the slot 6' is narrower than the large end of the 80 knife-guide, a spring action will be set up in each of said lips 5 and 6 and said knife-guide will be wedged in position in the slots 5' and 6' of the guide-holder. When the knife is inserted in the longitudinal slot 85 8 of the knife-guide it will tend to separate the legs of the U-shaped end portion and force them against the sides of the slot 6', thereby increasing the wedge action.

With the above construction of guide- 90 holder it will be seen that the knife-guide can be easily and quickly mounted therein or removed therefrom without the use of solder and without detaching the guide-holder from the machine. 95

What I claim as my invention and desire to secure by Letters Patent is:

1. An article of the character described comprising a body-portion provided with a slot upon one side arranged and adapted to 100 receive a removable U-shaped knife-guide.

2. An article of the character described comprising a wedge-shaped body-portion provided upon one side with a downwardly extending lip and an upwardly extending 105 lip, each of said lips being arranged to form a slot between the lip and the body-portion.

3. An article of the character described, comprising a body portion provided upon 110

one side with a narrow slot at the top and a wide slot at the bottom.

4. The combination with a guide-holder, comprising a body portion having a downwardly extending lip and an upwardly extending lip, of a knife-guide having a longitudinal slot, said knife-guide being mounted in said guide-holder between the up-

wardly extending lip and the body portion and the downwardly extending lip projecting into the longitudinal slot in said knife-guide.

LOUIS TOUPIN.
